UNITED STATES PATENT OFFICE.

RICHARD LORD, OF CEDAR RAPIDS, IOWA.

LOOSE-LEAF BOOK.

1,076,131.

Specification of Letters Patent. Patented Oct. 21, 1913.

Application filed January 24, 1911. Serial No. 604,337.

To all whom it may concern:

Be it known that I, RICHARD LORD, a citizen of the United States, residing at Cedar Rapids, in the county of Linn and State of Iowa, have invented new and useful Improvements in Loose-Leaf Books, of which the following is a specification.

This invention relates to loose leaf books, and consists in certain improvements in the 10 construction thereof as will be hereinafter fully described and pointed out in the claims.

It has been common in preparing leaves for loose leaf books to crimp or break the leaves along the line of the bend of the leaf 15 when the book is opened, the purpose being to make the leaf bend more readily, and thus make the working surface of the leaf substantially flat. This crimping or indenting the leaf for this purpose, however, has been 20 subject to the objection that it caused the book when closed to bulge more or less due to the fact that the indentations and protuberances in the different leaves do not exactly register.

25 Difficulty has been experienced in maintaining the several leaves of a loose leaf book in exact alinement or register. By crimping the leaves along those portions of the leaves which are between the binding 30 plates or along the line of the binding posts, the protuberances or indentations thus produced when bound in the book so come together as to maintain the several leaves of the book in exact alinement and register. 35 Furthermore, if the leaves are crimped along that part of the leaf extending inwardly from the binding posts sufficiently to permit of the easy bending of the leaves, the maintenance of the leaves in register by crimping 40 along that part obviates the difficulty heretofore experienced as to the bulging of the book when closed.

The invention is illustrated in the accompanying drawings as follows:

45 Figure 1 shows a plan view of a loose leaf. Fig. 2 an end elevation. Fig. 3 a perspective view of a loose leaf book containing the leaves similar to that shown in Figs. 1 and 2.

1 marks the leaves, 2 the opening in the 50 leaves for the binding posts. These may have the slot 3 extending to the edge so that the leaves may be removed without entirely releasing the posts. The binding plates 4—4 are secured by the binding posts 5, any of the 55 well known devices being used on the posts.

The edge of the leaves secured between the plates 4 have the corrugations 6 lengthwise of the plates 4. These corrugations 6 are in that part of the leaf along the line of posts where the posts are used, or between the binding plates so that these protuberances and indentations are subjected to the pressure of the binding plates. The several leaves are in this way brought into and kept in nice alinement and register. By extending the corrugations inwardly from the part between the plates to that part of the leaf which is bent in opening the book, the leaves readily yield so as to give a flat working surface. At the same time, they are 65 maintained in register so as to prevent the bulging which is ordinarily present.

In the drawings as shown, the corrugations are exaggerated and also the relative thickness of the leaves.

What is claimed as new is:

1. In a loose leaf book, the combination of binding plates; and leaves pressed between the plates and having registering indentations and protuberances in those parts

80 of the leaves between the plates and having corrugations lengthwise of the plates, said corrugations being in those parts of the leaves extending inwardly from the portions of the leaves between the plates.

85 2. In a loose leaf book, the combination of binding plates; and leaves pressed between the plates, said leaves having corrugations extending lengthwise of the plates, said corrugations being in those portions of the leaves between the plates and those subjected to flexure as the book is opened.

90 3. In a loose leaf book, the combination of binding plates; binding posts between the plates; and leaves having openings through which the posts extend pressed between the plates and having registering protuberances and indentations in those parts of the leaves along the line of the openings, and having corrugations along those parts 95 of the leaves extending inwardly from the binding plates.

In testimony whereof I have hereunto set my hand in the presence of two subscribing witnesses.

RICHARD LORD.
